UNITED STATES PATENT OFFICE

CLEMENT H. MACE, OF DENVER, COLORADO

SINTERING MACHINE

Application filed May 25, 1928. Serial No. 280,492.

My invention relates to apparatus for the roasting and sintering of ores, and it has for its principal object the provision of a roasting and sintering apparatus in which a movable igniter is associated with a sintering hearth for the main object of igniting a charge upon the hearth over a predetermined extent thereof.

Another object is to provide a sintering hearth at an incline to facilitate the removal of sinter.

A further object is to provide means for the quick ignition of material upon a defined area of the hearth.

Other objects reside in details of construction, which will more fully appear in the course of the following description.

In the drawings, in which like parts are similarly designated throughout the various

views,

Figure 1 is a partly broken plan view of an embodiment of my invention;

Figure 2, is an elevation looking in the direction of the arrow "A" of Figure 1, and

Figure 3 is a section taken on the line 3—3 of Figure 1.

Referring more specifically to the drawings, the reference numeral 5 represents a suction box having outlets 6 for its connection with a flue 60 in turn connected with a suction means (not shown), whereby the air is exhausted from the suction box. Channel irons 7 brace the suction box at its bottom. Angle irons 8 provide vertical braces at the front and rear of the apparatus.

On supports 9 running longitudinally of the suction box rest grate bars 10 inclined from the horizontal. A lining 12 in the upper portion of the suction box, together with the grate bars, define a chamber for retaining the ores to be roasted or sintered.

The chamber has openings 13 at its lower end and gates 14 at the front of the apparatus to close said openings during sintering or roasting, and permit the discharge of the roasted or sintered material thereafter.

The gates 14 are mounted on a shaft 15 that has a squared end 16 for the application

50 of a crank to open the gates simultaneously

by rotation of the shaft. Pivoted fasteners 17 hold the gates in their closed positions.

Fastened at the upper ends of the uprights 8 are channel bars 18, which together with the ends of the uprights, afford supports for rails 20 extending lengthwise of the apparatus. The structural bars 7, 8 and 18, assembled as shown and described, together constitute a frame that supports and braces the walls of the apparatus.

Traveling on the rails 20 is a wheeled carriage 21. The wheels of the carriage have been designated by the number 22 and are mounted on shafts 23.

One of the shafts is extended beyond the track and carries a hand wheel 24 for moving the carriage.

On the carriage is an igniter comprising a fuel tank 29, a motor 30, a fan 31 operated by the motor, and a hood, each of which will 70 hereafter be more fully described.

The fuel tank 29 is held on cross bars 33 of the carriage by means of clamps 34. A filler cap 35 is provided at the top of the tank to replenish the fuel therein. The motor 30 75 is bolted to a floor 36 of the car. The fan 31 is preferably mounted directly upon the rotor shaft 37 of the motor. Concentric pipes 38 and 39 connecting respectively with the fan and the fuel tank constitute the fuel oil 80 burner of the igniter.

The air discharged through the outer pipe, atomizes the fuel supplied through the inner pipe, and the ends of the pipe conjointly provide a nozzle at which the atomized fuel is 85 ignited.

A valve 40 controls the fuel supply through the fuel conduit 39 and a valve 41 regulates the air supply in the conduit 38.

The nozzle 32 projects into an opening 42 90 of the aforementioned hood 43 which comprises end walls 45 and side walls 45^a, an arched roof 45^a and a hollow apron 44 sloping downwardly from one of the end-walls. The walls of the hood are preferably composed of fire brick covered exteriorly by metal plates and interposed sheets of a non-conducting substance such as what is known in the trade as sil-o-cel.

The wall opposite to that from which the

apron projects, has interiorly a baffle 50 to deflect the heat and gases to the space beneath the apron which is provided with openings 48 for the admission of oxygen to the roasting-chamber.

In practice, the charge of fuel on the hearth will vary considerably in depth and since it is highly desirable that the hood be as close to the charge as possible and still clear it, the hood must be adjustable as to height.

The element provided to effect this adjustment comprises parallel shafts 51 and 52 mounted in bearings 53 on the cross bars 15 33 of the carriage. The shaft 51 projects beyond the track 20 and has a hand wheel 54 at its projecting end. The shafts carry aligned sprocket wheels 58 and 59 connected by a chain 61 by which the shafts 51 and 52 20 are caused to rotate simultaneously in the same direction when the hand wheel 54 is turned.

The hood is suspended from these shafts 51 and 52 by flexible cords 55 fastened to 25 and wound around the shafts, as shown at 62 in Figure 3. A ratchet wheel 56 on the shaft 51 and a therewith cooperating pawl 57 on the carriage frame, hold the hood in any adjusted position.

In practice, a charging car of conventional design may first be run along the track of the furnace to distribute a charge of ore over the hearth. The charge may be wet to promote the sintering action. Then the oil 35 burner of the igniter element is lit, the hood is adjusted so that it is in close proximity to the charge, and the carriage on which the hood and the igniter are supported, is propelled along the track by means of the hand wheel 24.

The nozzle of the burner slants upwardly in the opening 42 to project its flame along the arch and the baffle 50 directs the flame downwardly and across the hearth under 45 both the arch and the apron and toward and through the ore bed on the hearth, as indicated by the arrows in Figure 3. The openings in the apron afford an entrance for air to provide oxygen for the burner.

It will be seen that by movement of the carriage, which may be either continuous or intermittent, successive portions of the ore bed are progressively ignited and that in this manner an ignition element of comparatively small proportions and correspondingly simple construction may be employed to ignite the charge on a hearth of any desired length.

After the carriage has traveled the length 60 of the hearth, which may be considerably longer than shown, the ores have been ignited over their entire extent, and they are allowed to burn until the roasting or sintering operation is complete and the ore is formed into an agglomerated mass or cake.

The suction box 5 and the suction means with which it is connected, create a draft to draw the heat and gases of combustion through the grate bars, that is continued throughout the operation.

When the agglomeration of the ore has taken place, the fastenings 17 are moved to release the gates 14 and the gates are opened by rotation of the shaft 15 as described. A slice bar may then be inserted under the cake to release it from the hearth and allow it to slide through one of the gates and into any suitable receptacle.

It will be seen from the foregoing that a very practical and efficient apparatus for roasting or sintering crushed or fine ore, concentrates, flue dust, bag house fumes, or any fine material, has been provided.

Details of construction of the apparatus may be varied considerably without departing from the scope and spirit of the present invention and I do not wish to be limited to the construction shown and described except as specifically stated in the hereunto appended claims.

What I claim and desire to secure by Letters Patent is:

1. In apparatus of the character described, a hearth, a burner, and a hood for directing the flames of the burner toward a charge on the hearth, comprising in spaced relation to the hearth, an arched body portion and a laterally projecting apron apertured for the admission of air.

2. In apparatus of the character described, a hearth, a burner and a hood for directing the flames of the burner toward a charge on the hearth, comprising in spaced relation to the hearth, an arched body portion, a laterally projecting apron apertured for the admission of air and a baffle opposite the apron to direct the flames into the space beneath the same.

3. In apparatus of the character described, a laterally inclined hearth, a surrounding wall for the hearth, having a normally closed opening at the lower edge of the same for the removal of burnt material, and an ignition element movable along the hearth, including a burner and a hood restricting the action of the burner to a portion of the hearth beneath the same, exclusive of the other portion of the hearth.

4. In a sintering furnace, a hearth, a hood covering a portion of the hearth and comprising an expansion-chamber and a space of relatively small depth connected at the lower portion of the chamber to restrict heat to a region immediately above an ore bed on the hearth, and a burner for the projection of flames into the expansion chamber.

5. In a sintering furnace, a hearth, a hood covering a portion of the hearth and comprising an expansion-chamber having an arched roof and a space of relatively small depth

connected at the lower portion of the chamber to restrict heat to a region immediately above an ore-bed on the hearth, and a burner disposed to direct flames along the arched roof of the expansion chamber for their deflection toward and into the space of small depth.

6. In a sintering furnace, a laterally inclined hearth for the support of an ore bed, ignition means for the ore bed, an enclosure for the hearth, having an opening at the lower edge of the incline for the discharge by gravity of sintered cakes, and a door closing the opening.

10. 7. In a sintering furnace, a laterally inclined hearth for the support of an ore bed, ignition means for the ore bed, an enclosure for the hearth having a plurality of openings at the lower edge of the incline, for the discharge by gravity of sintered cakes, doors closing the openings, and mechanism for simultaneous opening of the doors.

15. 8. In a sintering furnace, a laterally inclined hearth, an enclosure for the hearth, having means for the discharge of sintered cakes at the foot of its incline, a hood covering the hearth laterally along a portion of its longitudinal extent, and a burner in the hood, the hood being movable lengthwise of the hearth to cover other similar portions of the hearth.

20. 9. In a sintering furnace, a hearth, a hood covering a portion of the hearth and movable lengthwise of the hearth to cover other similar portions of the same, a burner in the hood, means for the propulsion of the hood, and means for varying the elevation of the hood above the hearth to accommodate ore-beds of different heights.

25. 10. In a sintering furnace, a hearth, a hood covering a portion of the hearth and comprising an expansion-chamber, a space of relatively small depth connected at the lower portion of the chamber to restrict heat to a region immediately above an ore-bed on the hearth, and a baffle opposite the space to direct flames into the same, and a burner for the projection of flames into the expansion chamber.

30. 50. In testimony whereof I have affixed my signature.

CLEMENT H. MACE.
